UNITED STATES PATENT OFFICE.

BURNHAM C. STICKNEY, OF ELIZABETH, NEW JERSEY, ASSIGNOR TO
UNDERWOOD TYPEWRITER COMPANY, OF NEW YORK, N. Y., A
CORPORATION OF NEW JERSEY.

TYPE-WRITING MACHINE.

No. 851,142

Specification of Letters Patent.

Patented April 23, 1907.

Application filed October 31, 1906. Serial No. 341,476.

To all whom it may concern:

Be it known that I, BURNHAM C. STICKNEY, a citizen of the United States, residing in Elizabeth, in the county of Union and 5 State of New Jersey, have invented certain new and useful Improvements in Type-Writing Machines, of which the following is a specification.

This invention relates to that class of type-writing machines in which two ribbons are employed, either of which may be caused to vibrate to cover and uncover the printing point at the type strokes.

The principal object of the invention is to 15 provide simple, inexpensive and reliable means for enabling either ribbon to vibrate, so that either its upper edge or lower edge may overlie the printing point. Each ribbon may be provided with two color bands, 20 whereby the operator is enabled to make a selection from four colors; or one of the ribbons may be of one color and may be economically used along both top and bottom edges.

25 In carrying out my invention, I preferably employ a bipartite universal bar connected to the ribbon vibrators; or in other words two universal bars one for each vibrator and both controlled by the type keys. This 30 feature of the invention is also applicable to machines in which each ribbon has only one color, and is not adjustable to bring different widthwise portions thereof into use. Said universal bars I mount upon a single 35 frame which is adjustable to different positions to bring either universal bar into use and simultaneously silence the other. Provision is also made for enabling either universal bar to be given different strokes by 40 the type keys for imparting different strokes to the ribbon vibrators. Provision is further made for silencing both universal bars at will to enable the printing of stencils, in doing which the types should not strike 45 through a ribbon. I preferably connect to each universal bar, means acting directly upon its associated ribbon-spoils or spool-shafts, for winding its ribbon back and forth; and when either universal bar is silenced, 50 its ribbon neither vibrates nor winds. I provide a single finger-piece connected to the frame on which the universal bars are mounted, together with yielding means for

adjusting the finger-piece in different positions. It is preferably adjustable to five 55 positions, one for silencing both universal bars, and the remaining four for enabling either one or the other of the universal bars to impart different strokes to its associated vibrator. Other objects and advantages 60 will hereinafter appear.

In the accompanying drawings, Figure 1 is a sectional elevation from front to rear of a front-strike writing machine embodying my improvements; and Fig. 2 is a plan of the 65 ribbon mechanism.

Types 1 mounted upon type bars 2 strike rearwardly against the front side of a platen 3, the type bars being mounted in the usual manner upon a segmental fulcrum rod 4, and 70 operated in any usual manner, as for instance by links 5 and levers 6 bearing at their forward ends keys 7. The ribbons through which the types strike are superposed or arranged one behind the other, the front ribbon 75 8 being wound upon a pair of spools 9, 10, one at each side of the printing point, and the rear ribbon 11 being mounted upon a pair of spools 12, 13, between which the spools of the first pair are located. The front ribbon 8 is 80 threaded through a vibrator 14 which stands up from the forward end of a lever 15 fulcrumed at 16 upon the framework and having an arm 17 in rear of its fulcrum connected by a pendent link 18 to a universal bar 19. 85 Said universal bar extends horizontally across the machine beneath the key lever 6, and is mounted upon the rear ends of a pair of arms 20, which extend rearwardly from a rock-shaft 21, which is provided with a spring 22 90 to hold the universal bar up, or to return it to normal position after depression by the key levers. Said link 18 is attached at its lower end to a crank 23, which is fixed upon the rock shaft 21 about midway between the 95 ends of the latter. Each of the key levers has a projection 24, to engage said universal bar 19, to force down the universal bar and lift the vibrator 14 while the key is moving the type bar to the platen. Said shaft 21 100 has pendent cranks 25 to reciprocate a pair of pawls 26 adapted to engage ratchet wheels 27 fixed upon shafts 28, to which the spools 9 and 10 are fixed, whereby the ribbon 8 may be wound as well as vibrated by the universal 105 bar 19.

The rear ribbon 11 is threaded through a vibrator 29 upstanding from the front end of a lever 30 pivoted at 31 to the framework, and having a rearwardly extending arm 32, which is connected by an independent link 33 to a crank 34 projecting from a rock-shaft 35 parallel with 21, and having at its ends forwardly directed arms 36 supporting a universal bar 37 in rear of the universal bar 19. 15 The shaft 35 has a returning spring 37^a; undue elevation of the universal bar being prevented by a stop 38 engaging a shoulder 39 on the lever 30. A similar stop 40 is provided to engage a shoulder 41 formed upon the lever 15.

Pawl 42 extend forwardly from pendent cranks 43 upon the rock-shaft 35 to engage ratchet wheels 44 fixed upon shafts 45 upon which the spools 12, 13 are mounted. Friction springs 46, 47, bear upon the ratchet wheels to prevent back throw thereof.

At Fig. 1, the universal bar 37 is illustrated as silenced, so that its ribbon neither vibrates nor winds; while the forward universal bar 19 is shown in position to be actuated by the keys to both vibrate and wind the forward ribbon 8. For convenience in manipulating the universal bars to silence them and to enable either one to be shifted to different working position, I mount both upon a frame 48 which comprises a rock shaft 49 journaled in the sides 50 of the framework of the machine, and having upon the exterior of said framework an arm 51 provided with a finger-piece 52, whereby the frame 48 may be swung backwardly and forwardly. Upon the bottom of said arm is formed a notch 53 engaged by a spring detent 54 to hold the frame in position for the universal bar 19 to be engaged by the projection or step 24. 30

Upon swinging the frame 48 forwardly by means of the handle 52 until the detent 54 engages a notch 55 adjoining the notch 53, the universal bar 19 will be carried forwardly 45 to a position to be engaged by a stop 56 formed on each lever 6 just forwardly of the step 24, but not projecting so far below the lever, whereby the lever does not engage the universal bar during the first part of the key stroke, so that the movement imparted to the universal bar is lessened, and hence the ribbon vibrator 14 is given only a short up stroke, whereby the upper color band or edge thereof is caused to cover the printing point. 50

It will be understood that when the parts are at the Fig. 1 position, the universal bar 19 and vibrator 14 are given maximum strokes, whereby the lower color band or edge of the ribbon 8 is caused to cover the printing point 60 at the type strokes. It will also be understood that when the frame is swung forwardly to engage the detent 54 with the notch 55 as just explained, the universal bar 37 will still remain out of use or not engageable by 65 the key levers. Upon returning the frame

still farther forwardly by the finger-piece 52, so that the detent 54 engages the middle notch 56^a, the universal bar 19 is moved entirely away from the key lever projections, while the universal bar 37 is not yet brought 70 into position to be operated by the key levers, whereby both universal bars are silenced, and neither ribbon either vibrates or winds at the type strokes. Upon swinging the universal bar frame 48 still farther forward, so that the detent 54 engages the next notch 57 in the arm 51, the rear universal bar 37 is brought into position to be engaged by a rear step 58 formed upon each key lever, whereby the universal bar is given a short 80 stroke at the last portion of each key lever stroke, and the rear ribbon 11 is vibrated up to a position to enable its top portion or color band to cover the printing point; while the universal bar 19 is shifted still farther away 85 from the key lever steps. Upon shifting the frame still farther forward until the notch 58^a is engaged by the detent 54, the universal bar 37 is brought up to be engaged by the step 24 on each key lever, whereby said universal 90 bar is given a maximum stroke, and the ribbon 11 is vibrated up so that its lower edge or color band covers the printing point; while the universal bar 19 is shifted still farther away from the key levers. 95

It will be understood that when the detent 54 is in either of the last two notches 57, 58^a, the pawls 42 are actuated at the key strokes to turn the ratchets 44 to wind the ribbon 11. Any suitable springs 59 may be provided 100 however, for engaging the pawls with the winding ratchets, and they may be mounted upon a transverse horizontal bar 60 having stops 61 to oppose the springs 59 when the pawls are drawn back out of engagement with the ratchets. Said stops 61 also serve to unship the pawls at either the right hand or left hand side of the machine at Fig. 2, so as to cause the ribbons to wind back and forth upon the spools; the bar 60 having a finger-piece 62 for convenience in shifting, and any suitable detent as seen diagrammatically at 110 63 to engage notches 64 formed upon said bar. Each universal bar when in operation always actuates both its pawls, but either 115 one or the other of its pawls is always out of action according to the adjustment of the bar 60.

Many variations may be resorted to within the scope of the invention, which is not limited 120 so far as the selection of different colors or variable adjustment of the different ribbons is concerned to the employment of a bipartite universal bar, nor to the described winding mechanism; and portions of my improvements may be used without others, as for instance the frame 48 may be employed with only a single universal bar and a single set of steps on the key levers instead of a double set. 125 130

The two universal bars may be variously formed and located and operated within the scope of the invention, which is not limited to the use of one or both vibrators or universal bars operated directly by the key levers. The usual carriage feeding mechanism may comprise a third universal bar 65 connected by links 66 to an arm 67 of a rocker 68 having dogs 69, 70, to co-operate with an escapement rack 71 forming part of a carriage upon which the platen 3 is mounted.

Having thus described my invention, I claim:

1. In a typewriting machine having types and keys, the combination with a plurality of ribbon vibrators, of a plurality of universal bars operated by the keys and connected respectively to said vibrators.

2. In a typewriting machine having types and keys, the combination with a plurality of ribbon vibrators, of a plurality of universal bars operated by the keys and connected respectively to said vibrators, and means for silencing one of said universal bars while another is in operation.

3. In a typewriting machine having types and keys, the combination with two ribbon vibrators, of two universal bars, one for each of said vibrators, and means for silencing either universal bar and concomitantly rendering the other effective.

4. In a typewriting machine having types and keys, the combination with two ribbon vibrators, of two universal bars, one for each of said vibrators, and means for silencing either universal bar and concomitantly rendering the other effective.

5. In a typewriting machine having types and keys, the combination with two ribbon vibrators, of two universal bars, one for each of said vibrators, and means for silencing one universal bar and concomitantly rendering the other effective and for enabling the effective universal bar to impart different throws to its vibrator, to cause different widthwise portions of the ribbon to cover the printing point at the type strokes.

6. In a typewriting machine having types and keys, the combination with two ribbon vibrators, of two universal bars, one for each of said vibrators, and means for silencing either universal bar and concomitantly rendering the other effective and for enabling the effective universal bar to impart different throws of its vibrator, to cause different widthwise portions of the ribbon to cover the printing point at the type strokes.

7. In a typewriting machine having types and keys, the combination with two ribbon vibrators, of means for enabling keys to operate either vibrator and for enabling the throw of one of said vibrators to be varied, to bring different portions of the ribbon over the printing point at the type strokes.

8. In a typewriting machine having types

and keys, the combination with two ribbon vibrators, of means for enabling keys to operate either vibrator and for enabling the throw of either of said vibrators to be varied, to bring different portions of the ribbon over the printing point at the type strokes.

9. In a typewriting machine having types and keys, the combination with two pairs of ribbon spools and two ribbon vibrators, of two universal bars operated by the keys, one for each of said vibrators, spool-winding means controlled by the keys, and means for silencing either of said universal bars and concomitantly rendering the other effective and silencing the winding means associated with the silenced vibrator.

10. In a typewriting machine having types and keys, the combination with two pairs of ribbon spools and two ribbon vibrators, of two universal bars operated by the keys, one for each of said vibrators, two sets of spool-winding means respectively actuated by said universal bars, and means for silencing either of said universal bars and concomitantly rendering the other effective.

11. In a typewriting machine having types and keys, the combination with two pairs of ribbon spools and two ribbon vibrators, of two universal bars operated by the keys, one for each of said vibrators, two sets of spool-winding means respectively actuated by said universal bars, means for silencing either of said universal bars and concomitantly rendering the other effective, and a shifting device associated with said winding means, to cause either spool in either pair to wind.

12. In a typewriting machine having types and keys, the combination with two pairs of ribbon spools and two ribbon vibrators, of two universal bars operated by the keys, one for each of said vibrators, two sets of spool-winding means respectively actuated by said universal bars, means for silencing either of said universal bars and concomitantly rendering the other effective, and a shifting device associated with said winding means, to cause either spool in either pair to wind, said shifting device controlled by a single finger-piece.

13. In a typewriting machine having types and keys, the combination with two ribbon vibrators, of two universal bars, one for each of said vibrators, a single finger-piece, and means controlled by said finger-piece for concomitantly silencing either universal bar and rendering the other effective.

14. In a typewriting machine having types and keys, the combination with two ribbon vibrators, of two universal bars, one for each of said vibrators, a single finger-piece connected to means for concomitantly silencing one universal bar and rendering the other effective and for enabling the effective universal bar to impart different throws of its vibrator, to cause different widthwise portions of the ribbon to cover the printing point at the type strokes.

- point at the type strokes, and means for securing said finger-piece at different positions to which it is adjusted.
15. In a typewriting machine having types and keys, the combination of a shiftable frame, two universal bars mounted upon said frame and shiftable thereby into and out of position for operation, and ribbon vibrators connected to said universal bars.
16. In a typewriting machine having types and keys, the combination of a shiftable frame, two universal bars mounted upon said frame and shiftable thereby into and out of position for operation, and ribbon vibrators connected to said universal bars, said keys operating stepped-members which actuate said universal bars, and the latter being each shiftable to position for engaging with different stepped-members to vary the throw of its associated ribbon vibrator.
17. In a typewriting machine having a series of type bars, a series of key-operated levers connected to the type bars, the combination of a swinging frame, two universal bars hung upon said frame and movable thereby into and out of position to be engaged by stepped-projections upon said levers, a finger-piece for swinging said frame, means for detaining said frame in different positions, and ribbon vibrators respectively connected to said universal bars.
18. In a typewriting machine having types and keys, the combination with a plurality of ribbon vibrators, of means for enabling the keys to throw either of said vibrators different distances to bring different widthwise portions of the ribbon over the printing point at the type strokes.
19. In a typewriting machine having types and keys, the combination with a plurality of ribbon vibrators, of a plurality of universal bars operable by the keys and respectively connected to said vibrators, and means for either silencing one of said vibrators and concomitantly rendering the other effective, or silencing both of said vibrators, at will.
20. In a typewriting machine having types and keys, the combination with a plurality of ribbon vibrators, of a plurality of universal bars operated by the keys and respectively connected to said vibrators, and means for either silencing both of said universal bars or for silencing one of said universal bars and for concomitantly rendering the other effective.
21. In a typewriting machine having types and keys, the combination with two ribbon vibrators, of two universal bars, one for each of said vibrators, and a single device common to said universal bars and comprising means for either silencing either universal bar and concomitantly rendering the other effective, or silencing both universal bars concomitantly.
22. In a typewriting machine having types and keys, the combination with two ribbon vibrators, of two universal bars, one for each of said vibrators, an adjustable finger piece having means for concomitantly silencing either universal bar and rendering the other effective, and also for silencing both universal bars concomitantly, and means for detaining said finger piece in different positions to which it is adjusted.
23. In a typewriting machine having types and keys, the combination with two ribbon vibrators, of two universal bars, one for each of said vibrators, and means adjustable to different positions for either concomitantly silencing both universal bars or for silencing one universal bar and concomitantly rendering the other effective and for enabling the effective universal bar to impart different throws to its vibrator, to cause different widthwise portions of the ribbon to cover the printing point at the type strokes.
24. In a typewriting machine having types and keys, the combination with two ribbon vibrators, of means for enabling keys to operate either vibrator and for enabling the throw of one of said vibrators to be varied, to bring different portions of the ribbon over the printing point at the type strokes, and for silencing both vibrators at will.
25. In a typewriting machine having types and keys, the combination with two ribbon vibrators, of means for enabling keys to operate either vibrator and for enabling the throw of either of said vibrators to be varied, to bring different portions of the ribbon over the printing point at the type strokes, and for silencing both vibrators at will.
26. In a typewriting machine having types and keys, the combination with two pairs of ribbon spools and two ribbon vibrators, of two universal bars operated by the keys, one for each of said vibrators, spool-winding means controlled by the keys, and means for concomitantly silencing either of said universal bars and rendering the other effective, and for silencing the winding means associated with the silenced vibrator, and for concomitantly silencing both the winding means and the vibrators.
27. In a typewriting machine having types and keys, the combination with two pairs of ribbon spools and two ribbon vibrators, of two universal bars operated by the keys, one for each of said vibrators, spool-winding means directly actuated by said universal bars, and means for concomitantly silencing either of said universal bars and rendering the other effective, and for concomitantly silencing both universal bars, at will.
28. In a typewriting machine having types and keys, the combination with two ribbon vibrators, of two universal bars, one for each of said vibrators, a single adjustable finger-piece, means controlled by said finger-piece

for either concomitantly silencing either universal bar and rendering the other effective, or concomitantly silencing both universal bars, and means for detaining said finger-piece in different positions to which it is adjusted.

29. In a typewriting machine having types and keys, the combination of a shiftable frame, two universal bars mounted upon said frame and each shiftable thereby into and out of position for operation, and ribbon vibrators respectively connected to said universal bars; said frame movable to different positions for silencing both universal bars and for bringing either into use while the other is silenced.

30. In a typewriting machine having types and keys, the combination of a shiftable frame, two universal bars mounted upon said frame and shiftable thereby into and out of position for operation, and ribbon vibrators respectively connected to said universal bars, said keys operating stepped members which actuate said universal bars, and the latter being each shiftable to position for engaging with different stepped members to vary the throw of its associated ribbon vibrator, and said universal bars being also shiftable to positions where both clear said stepped members at the same time.

31. In a typewriting machine having a series of type bars, a series of key-operated levers connected to the type bars, the combination of a swinging frame, two universal bars hung upon said frame and movable thereby into and out of position to be engaged neither or either by stepped-projections upon said levers, a finger-piece for swinging said frame, means for detaining said frame in different positions, and ribbon vibrators connected to said universal bar.

32. In a typewriting machine having types and keys, the combination with a plurality of ribbon vibrators, of means for enabling the keys to throw either of said vibrators different distances to bring different widthwise portions of the ribbon over the printing point at the type strokes, and for silencing both vibrators.

33. In a typewriting machine having types and key, means for enabling the keys to vibrate any one of four bands of ribbon over the printing point at the type strokes, or for silencing the ribbon-vibrating mechanism.

34. In a typewriting machine, the combination with key levers having steps, of a universal bar, means for shifting said universal bar to positions to engage different sets of steps to be vibrated different distances at the type strokes, and a vibrator connected to the said universal bar.

35. In a typewriting machine comprising a type-operating mechanism, the combination with means for enabling the type-oper-

ating mechanism to vibrate a plurality of ribbons to cover the printing point, of means for enabling the operator to silence one ribbon and cause the type-operating mechanism to vibrate the other ribbon to bring different widthwise portions thereof over the printing point.

36. In a typewriting machine comprising a type-operating mechanism, the combination with means for enabling the type-operating mechanism to vibrate a plurality of ribbons to cover the printing point, of means for enabling the operator to silence either ribbon and cause the type-operating mechanism to vibrate the other ribbon to bring different widthwise portions thereof over the printing point.

37. In a typewriting machine having a platen and a type-operating mechanism, the combination of two pairs of ribbon spools, means between the spools for guiding the ribbons in superposed relation, means for winding either spool of either pair, and means for enabling the type-operating mechanism to cause the ribbon on either pair of spools to vibrate variably at the type strokes, to cause different widthwise portions of the ribbon to cover the printing point.

38. In a typewriting machine having a type-operating mechanism, the combination of two pairs of spools, of means for winding either spool of either pair, while the spools in the other pair remain stationary, and means for enabling the type-operating mechanism to cause the ribbon upon either pair of spools to vibrate during the type strokes, to cover and uncover the printing point; said vibrating means including a part adjustable to enable one ribbon to be vibrated variably by the type-operating mechanism, to cause different widthwise portions of the ribbon to cover the printing point.

39. In a typewriting machine provided with types and a platen, the combination of two pairs of spools, means for winding the ribbon back and forth upon either pair of spools, while the spools in the other pair remain stationary, and means for causing the ribbon upon the active spools to vibrate different distances at the type strokes, at the will of the operator, to cause different widthwise portions of the ribbon to cover the printing point.

40. In a typewriting machine, the combination with two pairs of spools, of a spool winding mechanism, a shifting device for connecting either pair of spools to said winding mechanism, and means connected to said shifting device for causing to cover the printing point different widthwise portions of that ribbon which is carried by the spools which are connected to the winding mechanism.

41. In a typewriting machine, the combination with two pairs of spools, of a spool winding mechanism, a shifting device for

connecting either pair of spools to said winding mechanism, and means operable simultaneously with said shifting device, for causing to cover and uncover the printing point at the type strokes different widthwise portions of that ribbon which is carried by the spools which are connected to the winding mechanism.

42. In a typewriting machine, the combination with a platen and types mounted to strike upon the front side thereof, of two pairs of spools mounted edge to edge in front of the platen, two spools at each side of the printing point, one pair of spools between the spools of the other pair, two vibrators for causing the ribbons to cover and uncover the printing point, a spool winder at each side of the printing point, means for effecting co-operation between said winders and either pair of spools, adjustable means for variably actuating the vibrator which is associated with the spools with which the winders co-operate, and means for reversing the direction of rotation of said winders.

43. In a typewriting machine, the combination with two pairs of ribbon spools, of actuating means for winding said spools, means movable independently of said spools for operatively connecting said pairs of spools alternately to the actuating means, and means for causing either ribbon to vibrate variably at the type strokes to cause different widthwise portions thereof to cover the printing point.

44. In a front strike writing machine, the combination with two pairs of ribbon spools placed edge to edge, of means for winding either spool of either pair, and means for causing the ribbon upon either pair of spools to move different distances to cause different widthwise portions thereof to cover the printing point.

45. In a front strike writing machine, the combination with a platen, of two pairs of ribbon spools mounted in front of the platen, one pair between the spools of the other pair, means for winding either spool of either pair, and means for causing different widthwise portions of the ribbon upon either pair of spools to cover and uncover the printing point.

46. In a typewriting machine, the combination with two pairs of spools, of means for winding either spool of either pair while the spools in the other pair remain stationary, and means for causing different widthwise portions of the ribbon upon one pair of spools to cover the printing point, and for rendering said ribbon ineffective and causing the other ribbon to cover the printing point.

47. In a typewriting machine, the combination with two pairs of spools, of means for winding either spool of either pair while the spools in the other pair remain stationary, and means for causing different widthwise

portions of the ribbon upon either pair of spools to cover the printing point during the type strokes, at will.

48. In a typewriting machine, the combination with a platen and types mounted to strike upon the front side thereof, of two pairs of spools mounted edge to edge in front of the platen, one pair between the spools of the other pair, means for causing the ribbon upon either pair to vibrate variably to cause different widthwise portions thereof to cover and uncover the printing point during the type strokes, and means for winding the ribbon back and forth upon either pair of spools while the spools in the other pair remain stationary.

49. In a typewriting machine, the combination with two pairs of spools, of a spool-winding mechanism, means for causing either pair of spools to be operated by said winding mechanism while the other pair remains stationary; and means for causing the ribbon upon either pair of spools to move different distances to cause different widthwise portions thereof to cover the printing point.

50. In a typewriting machine, the combination with two pairs of spools, of a spool-winding mechanism, a shifting device for connecting either pair of spools to said winding mechanism, and means connected to said shifting device for causing to cover the printing point different widthwise portions of that ribbon which is carried by the spools which are connected to the winding mechanism.

51. In a typewriting machine, the combination with two pairs of spools, of a spool winding mechanism, a shifting device for connecting either pair of spools to said winding mechanism, and means operable simultaneously with said shifting device, for causing to cover the printing point at the type strokes different widthwise portions of that ribbon which is carried by the spools which are connected to the winding mechanism.

52. In a typewriting machine, the combination with two ribbon vibrators and two pairs of ribbon spools for carrying the ribbons threaded through said vibrators, of a finger-piece, and means operable by the latter for both rendering either vibrator effective and the other vibrator ineffective and for causing different widthwise portions of the active ribbon to cover the printing point, at the will of the operator, and also for causing the winding of the ribbon which is threaded through the effective vibrator.

53. In a typewriting machine, the combination with means for supporting two ribbons and means for causing either ribbon to wind while the other remains stationary, of means for causing the winding ribbon to be vibrated variably to cover the printing point at the type strokes.

54. In a typewriting machine, the combi-

nation with means for supporting two ribbons of reversible winding means, a finger-piece, means controlled by said finger-piece for causing either ribbon to be wound by 5 said winding means while the other ribbon remains stationary, two vibrators for causing the ribbon to cover and uncover the printing point at the type strokes, and means also controlled by said finger-piece for calling 10 into action the vibrator which carries the winding ribbon and rendering the other vibrator ineffective, and for causing different widthwise portions of the active ribbon to cover the printing point, at the will of the 15 operator.

55. In a typewriting machine comprising a type-operating mechanism, the combination with means for enabling the type-operating mechanism to vibrate a plurality of 20 ribbons to cover the printing point, of means for enabling the operator either to silence both ribbons simultaneously, or to silence one ribbon and cause the type-operating mechanism to vibrate the other ribbon to 25 bring different widthwise portions thereof over the printing point.

56. In a typewriting machine comprising a type-operating mechanism, the combination with means for enabling the type-operating mechanism to vibrate a plurality of ribbons to cover the printing point, of means for enabling the operator either to silence both ribbons simultaneously or to silence either ribbon and cause the type-operating mechanism to vibrate the other ribbon to bring 35 different widthwise portions thereof over the printing point.

57. In a typewriting machine provided with types and a platen, the combination of 40 two pairs of spools, means for winding the ribbon back and forth upon either pair of spools while the spools in the other pair remain stationary, and means for causing the ribbon upon the active spools to vibrate 45 different distances at the type strokes, at the will of the operator, to cause different widthwise portions of the ribbon to cover the printing point; means being provided for silencing simultaneously the winding means 50 and vibrating means of both ribbons.

58. In a typewriting machine, the combination with two pairs of spools, of a spool winding mechanism, a shifting device for

disconnecting both pairs simultaneously or connecting either pair of spools to said winding mechanism, and means connected to said shifting device for causing to cover the printing point different widthwise portions of that ribbon which carried by the spools which are connected to the winding mechanism, or for silencing the widthwise movements of both ribbons simultaneously with the disconnection of the winding mechanism from both pairs of spools. 55

59. In a typewriting machine, the combination with two pairs of ribbon spools, of shiftable means for either silencing both ribbons simultaneously or causing the ribbon on either pair to vibrate to cover and uncover the printing point at the type strokes at will, 70 said shiftable means being also shiftable to cause different widthwise portions of the active ribbon to cover the printing point at the type strokes. 65

60. In a typewriting machine, the combination with two pairs of spools, of means for winding either spool of either pair while the spools in the other pair remain stationary, and means for causing different widthwise portions of the ribbon upon one pair of 80 spools to cover the printing point, and for rendering said ribbon ineffective and causing the other ribbon to cover the printing point, and for silencing all the ribbon-winding and moving means. 85

61. In a typewriting machine, the combination with means for supporting two ribbons of reversible winding means, a finger-piece, shiftable means controlled by said finger-piece for causing either ribbon to be wound by 90 said winding means while the other ribbon remains stationary, and two vibrators for causing the ribbon to cover and uncover the printing point at the type strokes, said shiftable means being provided 95 with means to call into action the vibrator which carries the winding ribbon and rendering the other vibrator ineffective, and to cause either vibrator to move variably at the type strokes, and to silence all the ribbon 100 winding and vibrating mechanisms.

BURNHAM C. STICKNEY.
